US0D1000039S

(12) **United States Design Patent** (10) Patent No.: **US D1,000,039 S**
(45) Date of Patent: ** Oct. 3, 2023

(54) **SHIRT**

(71) Applicant: **Minwoo An**, Incheon (KR)

(72) Inventor: **Minwoo An**, Incheon (KR)

(**) Term: **15 Years**

(21) Appl. No.: **29/820,648**

(22) Filed: **Dec. 23, 2021**

(30) **Foreign Application Priority Data**

Dec. 6, 2021 (KR) 30-2021-0058412

(51) **LOC (14) Cl.** **02-02**

(52) **U.S. Cl.**

USPC **D2/717**

(58) **Field of Classification Search**

USPC D2/717, 728, 741, 840, 844

CPC A41B 1/00

See application file for complete search history.

(57) **CLAIM**

The ornamental design for a shirt, as shown and described.

DESCRIPTION

The file of this patent or patent application contains at least one drawing/photograph executed in color. Copies of this patent or patent application with color drawing(s)/photograph(s) will be provided by the Office upon request and payment of the necessary fee.

The single view is a front elevational view of a shirt of the present invention.

The broken lines shown in the figure are for purposes of illustrating environmental structure and form no part of the claimed design.
